FIG. 3.

M. J. RYAN and G. F. JONES, INVENTORS

BY *J. P. Connor*
ATTORNEY.

UNITED STATES PATENT OFFICE.

MILES J. RYAN AND GEORGE F. JONES, OF SPRINGFIELD, MASSACHUSETTS.

ADVERTISING DEVICE.

Application filed January 19, 1921. Serial No. 438,426.

To all whom it may concern:

Be it known that we, MILES J. RYAN and GEORGE F. JONES, citizens of the United States, residing at Springfield, in the county of Hampden and State of Massachusetts, have invented certain new and useful Improvements in Advertising Devices, of which the following is a specification, reference being had to the accompanying drawing.

10. This invention refers to devices for attracting attention and more particularly to that class known in the commercial world as advertising devices. It has among its objects to provide such a device that will be particularly attracting; that will have facilities for self-contained illumination; that will be arranged for use on tables, lighting fixtures and the like that are suitable for the purpose in stores and other commercial locations; and to be arranged such that it will be adjustable and more definitely designate the thing that it is intended to attract attention to, and many other objects which will become apparent as the invention 25 is more fully set forth.

In the past the attractiveness of an advertised medium depended on features contained within itself or embodied actually on it in some way or form. The means used 30 are of indirect significance, they attract the eye and attention and hold sufficient view to make the observer take in other details in connection therewith. The action is plural and indirect. It assumes that the party 35 will look further than the arrangement that attracts his attention and thus enable the goods connected therewith to receive the desired commercial consideration. It should be noted that the secondary attention of the 40 observer is non-compulsory or actually suggestive. This invention goes positively into the phase of the commercial transaction and compels by an unmistakable suggestion that the observer look where it intends that he 45 should. The psychological difference in the two systems is remarkable and has very practical results to those that use this invention over the older systems. In the past the means used consisted mainly of printed 50 cards, ribbons, pictures and other devices of more or less remote connection with the article to be advertised. They attract and then require reading to understand that which they want the observer to see. This 55 device consists of a hand or arrow which is so conventionally compelling that the ob-

server follows with his eyes where it directs allowing but short while to spend and use upon the device itself. This device goes further, in that it provides means for 60 bringing the device in exact adjustment to where it is desired to direct. It is adjustable in several planes so as to bring itself into conformity with its surroundings and the articles it is connected with in an advertising way. The adjustment can be readily made at any time and without moving the device out of its general location.

In the drawings appended herewith, which illustrate modifications of this invention:—

Figure 1 represents a lighting fixture embodying this invention.

Figure 2 represents a modified construction applicable to table use and with an arrow indicator.

Figure 3 is a modification using a hand and arranged for table or counter use.

Figure 4 is a modification using a combination swivel and flexible arrangement for adjustment purposes.

Similar reference characters refer to similar parts throughout the drawings.

In the construction shown in the drawings, the reference character 1 represents an indicator which is either of a hand or arrow 85 form. This indicator is made of glass or other translucent material and is hollow or provided with a recess therein arranged to take an electric incandescent lamp 2. This lamp is suitably positioned in the same so 90 as to reflect its light throughout the indicator. The glass is also preferably colored or arranged to have the illumination spread throughout the indicator. The indicator is provided with a base portion 3 adapted 95 to be held by a type of shade holder 4. This holder is mounted on a socket 5 that holds the lamp bulb. The socket is held by a flexible member which preferably consists of conventional flexible tubing and this in 100 turn is connected with an attachment plug 7 that enables the fixture to be attached to any socket or lighting fixture.

In Figure 3 the socket is connected to a swivel connection 8 which permits the socket 105 to be turned in two planes, one being up and down in an oscillating way and the other in a horizontal rotating plane. The swivel is mounted on a stand 9, and this in turn on a box adapted to contain a battery for providing the current for the lamp, 110 as shown at 10. The base 10 shown in Fig-

ures 2 and 4 are adapted for plug connection. In Figure 2 an arrow indicator is used, and in Figure 4 the swivel and flexible tubing are provided. The manner of wiring 5 is not indicated as it is of conventional arrangement and generally understood. Any general means can be used for increasing or decreasing the tension or frictional resistance of the swivel, so that the device will 10 stay in the position in which it is moved.

The operation of the device is simple; it consists in the attaching of the device to a source of current, and then flexing the indicator to the position that will point out the 15 goods or articles to be designated. By reason of the flexible tube or the swivel, the indicator can be placed in any position that will make it point to a direction that the article is in. The form of the indicator 20 is such that it will attract attention and all the more if colored red or some other distinguishable color. There is room on the hand or arrow for some short slogan to be attached such as the term Bargains, 25 etc., as shown in the drawings. It is a compact device and free from complicated

mechanism or other arrangement that would interfere with its practical installation.

It is not desired to limit this application to the particular constructions shown in 30 the drawings or in any other way otherwise than limited by the prior art as it is understood that many other constructions could be made that embody the same principles and come within the scope of the appended claim. 35

Having thus described the invention, what is claimed is:—

An advertising device comprising a hand indicator of translucent material and with 40 an interior recess therein, a holder for the indicator, a socket for the holder, having a lamp therein adapted to fit in said recess and illuminate the indicator from the interior, and means for enabling the socket 45 and indicator to be turned and directed in vertical and horizontal planes.

In testimony whereof we hereunto affix our signatures.

MILES J. RYAN.
GEORGE F. JONES.
